US00D537063S

(12) **United States Design Patent** (10) **Patent No.:** **US D537,063 S**
(45) **Date of Patent:** **** Feb. 20, 2007**

(54) **PORTABLE PHONE WITH
INTERCHANGEABLE REAR COVERS**

(75) Inventors: **Sung-Kwon Kim**, Gwangmyeong-si (KR); **Sang-min Hyun**, Seoul (KR); **Chang-Soo Lee**, Incheon (KR)

(73) Assignee: **Samsung Electronics Co., Ltd.**, Suwon-Si (KR)

(**) Term: **14 Years**

(21) Appl. No.: **29/255,074**

(22) Filed: **Mar. 6, 2006**

(30) **Foreign Application Priority Data**

Sep. 9, 2005 (KR) 30-2005-0030664

(51) **LOC (8) Cl.** **14-03**

(52) **U.S. Cl.** **D14/138**

(58) **Field of Classification Search** D14/137, D14/138, 147-148, 247-248, 144, 496, 156, D14/341-347, 191, 192; 379/433.01-433.13; 455/575.4, 566, 575.1, 556.1, 556.2, 90.3, 455/41.2; D21/329, 331, 333; D16/208

See application file for complete search history.

(57) **CLAIM**

The ornamental design for the portable phone with interchangeable rear covers, as shown and described.

DESCRIPTION

FIG. 1 is a perspective view of the portable phone with interchangeable rear covers showing our design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, open view thereof;

FIG. 9 is a rear, open view thereof;

FIG. 10 is a rear view thereof showing a cover removed;

FIG. 11 is a rear view thereof with a first interchangeable rear cover; and,

FIG. 12 is a rear view thereof with a second interchangeable rear cover.

1 Claim, 8 Drawing Sheets
